DRYING-KILN.

1,290,778.

Specification of Letters Patent.

Patented Jan. 7, 1919.

Application filed March 19, 1917. Serial No. 155,712.

To all whom it may concern:

Be it known that I, ELMER E. PERKINS, a citizen of the United States, residing at Chicago, in the county of Cook and State of Illinois, have invented certain new and useful Improvements in Drying-Kilns, of which the following is a specification.

This invention relates in general to drying kilns and has more particular reference to 10 that type of kiln which is employed for drying lumber by what is called the open, or moist air, process.

These kilns are customarily provided with heat insulated walls but the inlet and outlet 15 flues for the kiln have been located within the walls themselves. The result of this construction is that the moisture within the kiln will feed by capillary attraction through the walls where they are joined by these 20 flues, thus not only depriving the kiln of the necessary moisture but also eventually destroying the structure of the wall. Furthermore, since the temperature of the outer wall of the kiln structure is usually considerably 25 less than the inner wall it necessarily follows that the temperature within both the inlet and outlet flues will be less than the temperature inside the kiln, and consequently, variations in the outside temperature will 30 materially affect the circulation of air through the flues. It sometimes happens that the temperature of the inlet flues becomes higher than the temperature of the outlet flues, with the result that circulation 35 in the kiln is entirely stopped or sometimes it is even reversed so that the air flows in through the outlet flues and out through the inlet flues. To overcome this difficulty encountered in the operation of the kilns it 40 has heretofore been proposed to heat the air in the outlet flues by means of steam pipes disposed within these outlet flues, so that the air in the flues will be heated and caused to rise, thereby drawing the air from the interior 45 of the kiln and establishing the requisite circulation.

One of the primary objects of my present invention is to obviate all of the difficulties heretofore encountered, by reason of the location of the inlet and outlet flues in the hollow walls of the kiln structure, and with this end in view I propose to arrange both the inlet and outlet flues within the kiln or drying room itself where they are uninfluenced by variations in outside temperature.

Another object of my invention is to insure outflow of air through the outlet flues without resorting to steam pipes or other heating means within the flues, the outflow in the present instance being maintained by 60 atmospheric conditions within the kiln itself.

A further object is to provide a kiln in which the circulation can be regulated and controlled at will, and so constructed that the circulation may be entirely shut off until 65 the material to be dried has been heated and steamed to the requisite degree, whereupon the circulation may be established within the kiln to produce the desired moist air drying and finally the circulation may be increased 70 so as to permit the material to cool in such a way that all stresses and strains are removed from the material before the material is taken out.

Still another object is to so construct and 75 arrange the air intake flue to the kiln that the air will be thoroughly distributed and uniformly delivered to the kiln throughout its entire length so as to result in a uniform drying of all the material in the kiln. 80

Other objects and advantages of my present invention will be readily appreciated by those skilled in the art as the same becomes better understood by reference to the following description when considered in connection with the accompanying sheet of drawings.

Referring to the drawings, the single figure shows a perspective view of the interior of a kiln embodying my invention.

On the drawings, reference characters 3 and 4 indicate the side walls of my kiln, and 5 and 6 the floor and ceiling respectively, all of the walls being preferably constructed to provide suitable dead air spaces so that the 95 room will be adequately heat-insulated to prevent dissipation and loss of heat from the interior of the kiln.

A plurality of tracks 7, preferably three in number, are supported approximately two 100 and one-half feet above the floor 5 upon suitable supporting columns 8, these tracks being adapted to support the lumber or other material to be dried which may be piled directly upon the tracks or, as is customarily done, it may be run into the room upon trucks or car bunks constructed to travel upon these tracks.

Upon the columns 8 beneath the tracks 105 are securely mounted a series of transversely 110

extending beams or channel bars 9 which serve as supports for the heating pipes 11, preferably arranged in sections and connected at their ends with header pipes 12, 5 steam being supplied to the headers at one end through supply pipes 13 and exhausted from the other end through the delivery pipes 14. For the purpose of producing the requisite humidity within the kiln I employ 10 a steam-spraying pipe 15, of any preferred construction, through which steam is admitted directly into the kiln. All of these steam supply pipes are, of course, equipped with manually or automatically operable 15 valves, by means of which the temperature and humidity of the kiln may be controlled. Air is admitted to the kiln through an inlet flue 16 which is arranged entirely within the kiln adjacent to one lower corner thereof, the intake end 17 of the flue being located at one end and outside the kiln and equipped with a manually operable valve or 20 damper 18, by means of which the inflow of air may be controlled. By locating the intake 25 flue within the kiln itself instead of within the hollow side-walls, the flue is not affected by outside temperature changes, and furthermore, the heat insulating properties of the side walls are not impaired nor is there any 30 solid connection between the inner and outer walls through which moisture can escape from the kiln by capillary action so as to impair the efficiency of the kiln or injure the structure of the side-walls. 35 For the purpose of insuring an even distribution of the inflowing air throughout the length of the kiln the flue 16 is provided with a plurality of upwardly extending delivery branches 19, 21, 22 and 23 respectively, which, as will be seen from the drawings, increase in length from the intake end 40 of the flue 16. Since the air in the kiln is cooler at the bottom than it is nearer the top it will be obvious that the longer delivery 45 branches will be heated to a higher temperature by the surrounding air within the kiln than the shorter branches. Consequently, a greater draft will be created by the longer branches, but since the longer branches are 50 more remote from the intake end of the flue it will be obvious that this increased draft will be balanced by the tendency of the air to escape through the first branches encountered in its passage through the flue, 55 with the result that the air will be delivered from all of the branches in substantially equal amounts, so that uniform distribution through the kiln is secured, which results in uniform drying of all of the material. 60 The air is permitted to escape from the kiln so as to maintain the requisite circulation therein through a plurality of outlet flues, designated generally by reference character 24. These flues extend directly through the 65 ceiling of the room and are preferably

equipped at their upper delivery ends with caps or windshields 25 and also provided outside the kiln itself with valves or dampers 26, by means of which the flow of air through the flues may be controlled or shut off as occasion requires. It will be observed 70 that these flues instead of being disposed within the hollow side-walls of the kiln project directly downwardly into the kiln itself so that they are entirely surrounded by the 75 air within the kiln and are subjected to the temperatures of the kiln. Since the hottest and most moist air is near the ceiling of the kiln it will be obvious that the outlet flues will be heated near the top of the kiln to a 80 higher temperature than their lower ends. When the dampers 26 are open this difference in temperature between the upper and lower ends of the flues will cause the air to flow upwardly in the flues and be delivered 85 from the kiln, thereby establishing and maintaining a circulation within the kiln.

Since it is desirable to maintain a high degree of humidity in the kiln during the drying operation in order to prevent case-hardening and checking of the material being dried, it is desirable to maintain the 90 requisite circulation without reducing the humidity, and to obtain this result my outlet flues are extended downwardly to a 95 point substantially level with the bottom of the material being dried. The air at this level in the kiln carries the least moisture so that the air flowing outwardly from this level through the outlet flues reduces the 100 humidity a minimum amount for a given volume of air circulation.

For some materials it is desirable to increase the rapidity of the air circulation within the kiln and even when drying lumber, after the drying operation has been 105 practically completed, it is desirable to remove the air with its entrained moisture and permit the material to cool down before being removed. For the purpose of meeting 110 these requirements I have provided my outlet flues with a plurality of joints, indicated generally by reference characters 25 and 26. While only two joints are shown it will be obvious that a greater number 115 may be employed if desired. These joints are formed by hinging the sections of the flue together at one side and providing the opposite with a spring catch which will hold the sections in alignment in fully extended 120 position for normal operation. When it is necessary or desirable to increase the rapidity of the circulation the lower section of one or more of the flues may be swung upwardly into horizontal position, as shown in 125 full lines on the closest flue in the drawings. If still greater rapidity is desired both sections may be swung into horizontal position as shown in full lines in the middle flue, normally however, all of the flues are 130

in extended position, as indicated in full lines by the last flue shown and also by dotted lines showing the normal position of the other two flues. The sections of the flues 5 may be swung upwardly by any approved mechanism, but in the present instance I have shown a longitudinally movable rod 27 supported in suitable hangers 28 and connected with the lower end of each flue by 10 cables 29. One end of the rod extends outside the kiln and by moving the rod longitudinally the flue sections may be swung upwardly into horizontal position, as shown in the drawings.

15 For drying lumber the normal operation of my kiln is substantially as follows: After the kiln has been filled the doors are closed, also the dampers 18 and 26 on the inlet flues and the outlet flues. Steam is then admitted 20 through the pipe 15 in order that the direct action of the steam upon the lumber will cause the lumber to absorb the heat of the steam and condense the moisture on the outside, from whence it will be gradually evaporated as the lumber becomes thoroughly 25 heated, the thorough moistening of the lumber producing a perfect capillary action from the center which permits the lumber to dry from the center outwardly and prevents 30 case-hardening and checking. After the lumber has been thoroughly moistened and heated the direct steam through the pipe 15 is turned off and heat given off by the steam pipes 11 is relied upon to maintain the 35 requisite temperature. The damper 18 in the inlet flue and the damper 26 in the outlet flues are now opened so as to establish a circulation of air through the kiln without any direct change from the point of saturation 40 produced by the direct steam to a condition of moist air drying. The percentage of humidity is gradually reduced as the evaporation ceases and the temperature rises. In the last stage of drying the outlet flues 45 are broken at the point near the ceiling permitting a rapid escape of the air and moisture from the kiln at the same time the steam is shut off from the radiating pipes 11 and the inlet flue is left fully open, with the 50 result that the lumber is gradually cooled so as to relieve it of all stress and tension before being removed from the kiln.

It will thus be obvious that I have provided a kiln which is highly efficient for 55 moist air drying, which thoroughly distributes the air within the kiln so as to uniformly dry all of the material therein and which can be controlled so as to satisfactorily and efficiently meet all of the requirements of successful moist air drying. The details of construction illustrated and

described are, of course, capable of considerable modification and variation without departing from the essence of the invention as set forth in the following claims.

65

I claim:

1. A drying kiln having heat insulated walls, heating means arranged within said kiln, an outlet flue extending downwardly into the kiln so as to be heated by the surrounding air within the kiln, and means for varying the amount of projection of said flue downwardly into the kiln.

70

2. A drying kiln having heat insulated walls, heating means arranged within the kiln, and an outlet flue extending downwardly into said kiln, said flue being jointed within the kiln so as to permit the lower end thereof to be swung into inoperative position to thereby reduce the effective length of 80 the flue.

75

3. A drying kiln having heat insulated walls, heating means arranged within the kiln, and an outlet flue projecting downwardly into the kiln and provided with a plurality of joints intermediate its ends so that the effective length of said flue may be varied.

85

4. A drying kiln having heat insulated walls, heating means arranged within the kiln, an air inlet flue disposed within the kiln near the bottom thereof and provided with an air inlet opening outside the kiln, and a plurality of discharge branches communicating with said flue and extending upwardly into the kiln, said branches being of gradually increasing length from the intake end of the flue to the opposite end thereof.

90

5. A drying kiln having heat insulated walls, heating means arranged within the kiln, an air intake flue extending longitudinally of the kiln adjacent one of the lower corners thereof and having an air intake opening outside the kiln, a valve for controlling the supply of air to the kiln through 100 said flue, and delivery branches extending from said flue upwardly into the kiln, said branches being of gradually increasing length from the intake end of the flue.

105

6. A drying kiln having heat insulated walls, an air intake flue arranged within the kiln and having delivery branches extending upwardly into the kiln gradually increasing distances from the intake end of the flue, a valve for controlling the supply of air to the 110 kiln through said flue, a plurality of outlet flues extending downwardly into the kiln, said flues being adjustable as to length so as to vary the rapidity of the outflow of air from the kiln, and a controlling valve disposed in each of said outlet flues.
